(57) **CLAIM**

The ornamental design for a spoon rest, as shown and described.

DESCRIPTION

FIG. 1 is a perspective view of a spoon rest showing our new design;

FIG. 2 is a front elevational view thereof;

FIG. 3 is a top plan view thereof; and,

FIG. 4 is side elevational view thereof.

The broken-line disclosure of elements in the views is for illustrative purposes only and forms no part of the claimed design.

The portion of the peripheral member that is shown broken away indicates that the space between the two ends may vary.

The cross-hatching does not indicate a type of material, but only identifies the section break.
